UNITED STATES PATENT OFFICE

1,959,013

CONNECTOR

Robert S. Wentworth, Providence, R. I., assignor
to National Radiator Corporation, Johnstown,
Pa., a corporation of Maryland

Application April 17, 1933, Serial No. 666,490

16 Claims. (Cl. 257—151)

This invention relates to room heating appliances, and more particularly to that type of appliance designed for use in a cabinet and known in the art as "convectors". More specifically, the invention is for an improvement in convectors of the type shown in my copending applications Serial No. 513,883 now Patent No. 1,912,556, dated June 6, 1933, and Serial No. 514,164, now Patent No. 1,888,545, dated November 22, 1932.

In said copending applications I have shown a convector comprising a plurality of sections arranged side-by-side, each section comprising an inclined barrel having a header portion at the top and a header portion at the bottom, and having a plurality of heat dissipating fins on the side faces thereof. These fins form, in effect, a number of relatively short vertically extending air passages, the fins being inclined with respect to both the longitudinal and transverse axes of the barrel. With this arrangement the air rises up on the underside of the convector, passes through the channels defined by the fins, and discharges on the upper side of the convector. The whole structure is enclosed in a casing forming a flue or draft head. An effect is produced by such an arrangement comparable to that of a horizontally disposed convector having fins thereon forming vertical air passages.

At the same time, by reason of the slope, the cabinet or housing for the convector is of relatively less depth than would be required for a convector having horizontal barrels with vertical fins similarly placed.

In a convector of this type it is desirable to provide as much heat radiating surface in a cabinet of given dimensions as possible. At the same time, provision must be made for connecting the convector into the hot water or steam heating system together with the usual valves, pet-cocks, and sometimes humidifiers.

The present invention provides an end section for use with convectors of this type which are adapted for connection into heating systems of various types, permitting the pipes to go into the bottom of the convector or into the ends at either the top or bottom, which are arranged with fins for cooperation with the other sections of the convector and which permit the piping to be positioned in the center of the cabinet instead of forwardly or rearwardly of the center, and which provide a large heat dissipating surface. Instead of providing less heat dissipating surface at the ends of the convector than in the other sections, they provide more.

The invention, moreover, is adapted to either convectors of the single tier type or convectors of the multiple tier type.

The invention may be readily understood by reference to the accompanying drawings in which

Figure 1 represents, in elevation, a convector of the single tier type embodying my invention;

Figure 2 is an end elevation of the end section, looking at the outside of the section;

Figure 3 is a transverse horizontal section in substantially the plane of line III—III of Figure 2;

Figure 4 is a view similar to Fig. 2 showing an end section for a multi-tier convector;

Figure 5 is a side elevation of the end section shown in Fig. 4; and

Figure 6 illustrates more or less conventionally a typical installation for a multi-tier convector.

Referring first to the embodiments shown in Figs. 1 to 3, inclusive, the convector unit comprises a number of intermediate convector sections 2 which are preferably of the type shown in my Patent No. 1,888,545, characterized by the provision of upper header portions 3, lower header portions 4 connected by thin flat barrels 5 which are turned edgewise, and which are provided on each side face thereof with an upper series of fins and a lower series of fins which are staggered with relation to each other. In Figure 1 these fins are designated 6, and are staggered in a manner generally similar to the dotted line position of the fins appearing in Fig. 2 of the drawings, and which will be hereinafter more fully described.

As stated above, this construction of the sections 2 is disclosed and claimed in my said Patents 1,888,545 and 1,912,556. The convector sections 2 are supported between end sections 7, which sections are similar to each other, but which are reversed by reason of their being positioned at opposite ends of the convector. Each of the end sections 7 comprises a hollow rectangular panel having an outer face 8 and an inner face 9, the hollow interior of the panel forming a vertical chamber designated 10. On the outer face 8 near the top of the panel is cast a boss 11 tapped to receive a plug 12, the plug 12 being removable so that when desired a steam or water pipe can be screwed into this opening, which communicates with the interior chamber 10. The boss 11 is centered on the vertical center line of the section. At the bottom of the section there is cast another boss 13 having a downwardly extending portion 14. The boss 13 and 110

the portion 14 each have an interior passageway opening into the chamber 10, and each has a threaded opening for the reception of a plug 15 or of a water or steam pipe. I have shown plugs 5 in all of these threaded openings in the bosses 11, 13 and 14, but it will be understood that in different heating plants different openings would be used for steam pipes or water pipes, in which case the plugs at the desired points would be replaced by pipe connections. On the inner face of each of the end sections on the upper rear corner thereof there is a boss 16 which is faced to contact with the header portion 3 of the adjacent intermediate section. This boss 16 has an 10 opening to receive a force nipple of the type commonly employed in connecting radiator sections, and which is not shown, whereby water or steam may circulate from the chamber 10 in the end panel into or out of the intermediate sections. 15 Diagonally opposite the boss 16 on the inner face of the end section is a similar boss 17. Location of the boss 17 is therefore, in this particular structure, near the bottom of the end section and in front of the vertical center line of 20 the section. This boss, like the boss 16, is shaped and faced for cooperation with the corresponding header portion 4 of the adjacent intermediate section.

The width of the end sections corresponds approximately to the width of the interior of the cabinet in which the convector is adapted to be housed, and the positions of the bosses 16 and 17 assures the intermediate sections being sloped upwardly and rearwardly for the purpose described in my said copending applications and patents, and where slope in this direction is desired. Cast on the inner face of each of the end sections are heat dissipating fins adapted to register with the fins of the adjacent intermediate sections. In the convector illustrated, I have shown two series of fins 18 and 19 on opposite sides of the line of center of the bosses 16 and 17, the fins of one series being staggered or offset with respect to the fins of the other series, the fins being coextensive with and adapted to register with the fins of the adjacent intermediate section.

The end sections have lug portions 20 at diagonally opposite corners for tie bolts 21 for holding the assembly together. At the bottom of each end section are endwise projecting lugs 22 which are internally threaded to receive the threaded ends of supporting legs 23, 24 designates lock nuts on the threaded upper ends 55 of these legs.

Each of the end sections does not exceed in its overall width the space required for one of the intermediate sections. This is of advantage, because in estimating required radiation, the 60 number of sections may be specified with the knowledge that as far as width is concerned the end sections merely replace intermediate sections. The fin or extended area on the end sections is materially less than the extended area on the intermediate sections, and the placing of fins on the outer faces of the end sections would be of relatively little value compared with the increased weight, because such fins would have 65 no adjacent fins for cooperation therewith, with the result that there would be no substantially closed air passages provided for a relatively high velocity of air circulation between the fins. Compensation is therefore effected by reason of 70 the fact that the end sections provide a relatively 75

greater prime surface for the dissipation of heat than do the intermediate sections.

In order to keep the overall width of the end sections the same as the overall width of the intermediate sections and still provide for the necessary pipe connections in the portions 14, the portions 14 are offset inwardly toward the inner face of the convector, thus enabling the portions 14 to be of the diameter necessary for standard piping used in heating systems, and still maintain the portion 14 within the overall limits of the end sections.

The outer faces of the end sections may also be provided with such additional bosses as may be required for pet-cock connections or humidifier connections. In the upper part of the section above the boss 11 is a small boss 25, in which I have shown a plug 26. The plug 26 may be replaced by a pet-cock or an air escape valve of some kind. The outer face of the section may also be provided with a boss 27 in which I have shown a plug 28. A pipe may be substituted for the plug 28 where connection is to be made from the heating system to an air valve, as is well understood by those skilled in this art.

The advantages of the invention reside in the provision of a channel-like end section serving to substantially close the ends of the convector, having fins thereon which register and cooperate with the fins of the adjacent convector sections 105 and having nipple ports thereon so positioned as to assure the proper slope of the convector. A further advantage is that provision is made for bringing the pipes into either the bottom or the lower outside face or the upper outside face of 110 the convector with such pipes at the vertical center of the convector instead of forwardly or rearwardly, as would be necessary if the pipes had to be connected directly to the top or bottom of the inclined intermediate sections. A 115 further advantage is that the end sections provide a large prime heating surface to compensate for the relatively smaller extended heating surface and in the fact that the overall width of the end sections is approximately the same as the 120 overall width of any of the intermediate sections.

A still further important advantage of this type of end section is that the convector sections, which have relatively thin fragile fins, lie entirely within the area of the rectangular end 125 panels, as will be evident from an inspection of Fig. 2, with the result that when the convectors are boxed for shipping, or are being transported, there is little likelihood of the convector being damaged, particularly the fins, because all of the 130 fins lie within the confines of the rectangular panels.

Under some conditions it is desirable to arrange the convectors in tiers so as to provide in a relatively small compact unit a convector having a relatively large heat dissipating area with a maximum of fin space. For such an arrangement the construction shown in Figs. 4 and 5 is employed. I have illustrated an end section in these figures for a unit having three tiers of 140 convectors.

The general construction of the end section is not materially different from that previously described. It comprises a substantially rectangular hollow panel 30 having an outer face 31 and 145 an inner face 32. The outer face is provided with bosses at 33, 34 and 35 which may be plugged, or through which a connection may be made to the water or steam pipes of the system. The sections are relatively higher, however, than 150

the end sections shown in Fig. 1. On the inner face thereof are a plurality of pairs of bosses, the bosses of each pair being diagonally disposed with reference to one another.

5 In the construction shown in Fig. 4 the first pair of bosses comprises an upper boss 36 and a lower boss 37, the boss 37 of course being on the inner face of the panel and being similar to the bosses 16 and 17 in that they are adapted 10 to register with the header portions of the adjacent convector sections. The second pair of bosses 38 and 39 are similarly constructed and are equi-distantly spaced below the bosses 36 and 37, respectively, so that a second tier of convectors below the first one will be substantially 15 parallel with the first tier. The third pair of bosses 40 and 41 are similar to 36 and 37 and are spaced below the bosses 36 and 37 an equal distance so that a third tier of convector sections 20 may be placed below the second and be parallel therewith.

On the inner face of these panels are cast a series of fins 42, 43 and 44 arranged to register with the fins of a correspondingly positioned 25 convector and to complement the fins of adjacent convector sections, the upper series of fins 42 being disposed between the diagonally disposed nipple ports 36 and 37, the middle series of fins 43 being disposed between the diagonally 30 arranged nipple ports 38 and 39, and the lowermost series of fins 44 being located between the diagonally disposed nipple ports 40 and 41.

I have shown in Figs. 4, 5 and 6 bosses 55 on the inner face of the end section adjacent the bottom thereof and offset with respect to the vertical center line of the section and with respect to the boss 35. This arrangement permits of the connecting pipe to come up on the inside of the end section, as shown in Fig. 6, instead of on the 40 outside. This has an advantage in that the enclosure need only be as wide as the convector unit, and no space beyond the end sections has to be left for pipes and pipe connections. While I have not shown a connection boss so located 45 in the construction shown in Figs. 1 and 2, it is apparent that this feature may be included on the end section for a single tier convector as well as on an end section for a multiple tier convector.

50 The provision of a number of parallel tiers of convectors arranged in spaced relation gives a greater effective distribution of the extended area provided by the fin surfaces than would be obtainable in a single convector having a total vertical height equal to the height of the three tiers placed one on top of another.

In Fig. 6 I have shown a typical embodiment of a heater of the multiple tier type in which the convector unit or heater designated 50 is disposed in an enclosure 51 constituting a vertical flue, with an air inlet opening near the bottom at 52 and discharge through a grille 53 at the top. The enclosure is illustrated as being built 60 within a seat such as is commonly provided in railway stations and similar public places. The enclosure is of sufficient height so as to furnish a considerable draft head so as to insure the travel of air through the convector at a relatively high 65 velocity, more effective heating being secured through the heating of a larger volume of air in a given period of time to a lesser degree of temperature than by heating a smaller volume of air to a relatively higher temperature in the same 70 period of time, the former method securing a 75

better and more even diffusion of the heat through the room.

It will be understood that while I have shown three tiers of convectors in the multiple tier type, this is merely an arbitrary number, and that a different number may be employed according to the particular installation for which the unit is 80 designed.

The end sections in the multiple tier type of convector have all of the advantages of the end section described in connection with the single tier convector shown in Figs. 1 to 3, inclusive. Instead of showing in the multiple tier convector a connector similar to the connector 14 of Fig. 1, I have shown a connector 46 on the inside face 85 of the panel offset with respect to the vertical center line thereof, this being desirable for the particular installation shown in Fig. 6, but it will be understood that where desired the downwardly opening center connector 14 of Fig. 1 90 can be substituted for the arrangement shown in Fig. 4.

While I have shown certain particular preferred embodiments of my invention, it will be understood that various changes and modifications may be made therein without departing from the spirit of my invention and the scope 100 of the following claims.

I claim:

1. An end section for convectors comprising a substantially rectangular panel having a diagonally extending series of closely spaced fins on the inner face thereof and having a nipple port at each end of the series of fins, the nipple ports being adapted to register and connect with the header portions of a sloping fin convector and the fins being arranged to register with the fins of a sloping fin convector. 105

2. An end section for convectors comprising a substantially rectangular panel having a diagonally extending series of closely spaced fins on the inner face thereof all of which are substantially parallel and having a nipple port at each end of the series of fins, the nipple ports being adapted to register and connect with the header portions of a sloping fin convector and the fins being arranged to register with the fins of a sloping fin convector, said panel being hollow and having connector portions thereon for connecting the convector to a heating system, said portions being centered at substantially the vertical center 110 line of the panel. 115

3. An end section for convectors comprising a substantially rectangular panel having a diagonally disposed series of fins on the inner face thereof and having a nipple port at each end of the series of fins, the nipple ports being adapted to register and connect with the header portions of a sloping fin convector and the fins being arranged to register with the fins of a sloping fin convector, said panel being hollow and having connector portions thereon for connecting the convector to a heating system, said portions being centered at substantially the vertical center line of the panel, one of said connector portions 120 opening downwardly and being inwardly offset. 125

4. An end section for convectors comprising a substantially rectangular panel having a diagonally disposed series of fins on the inner face thereof and having a nipple port at each end of the series of fins, the nipple ports being adapted to register and connect with the header portions of a sloping fin convector and the fins being arranged to register with the fins of a sloping fin convector, said panel being hollow and hav- 130 135 140 145 150

ing connector portions thereon for connecting the convactor to a heating system, said portions being centered at substantially the vertical center line of the panel, said connector portions being located on the outside face of the panel.

5. An end section for convectors comprising a substantially rectangular panel having a diagonally disposed series of fins on the inner face thereof and having a nipple port at each end of the series of fins, the nipple ports being adapted to register and connect with the header portions of a sloping fin convactor and the fins being arranged to register with the fins of a sloping fin convactor, said panel being hollow and having connector portions thereon for connecting the convactor to a heating system, said portions being centered at substantially the vertical center line of the panel, said connector portions being located on the outside face of the panel, another 20 of said connectors being directed downwardly from the bottom of the panel.

6. An end section for multiple tier convectors comprising a hollow substantially rectangular panel having a plurality of series of sloping fins 25 on the inner face thereof, each series of fins being arranged in a diagonal direction across the inner face of the panel, the different series of fins being arranged at different vertical elevations, the inner face of the panel being provided with a nipple port at each end of each series of fins.

7. A convactor of the inclined sloping fin type comprising a plurality of inclined sections, each having a barrel portion with a header at the top thereof and a header at the bottom thereof, and each having sloping fins on the opposite side faces thereof, the fins of one section registering with those of another, and end sections at each end of the convactor, each end section 40 comprising a hollow rectangular panel having a diagonally disposed series of fins on the inner face thereof coextensive with and registering with the fins of the adjacent intermediate sections, each end section also having a nipple port on the inner face thereof at the top of said series of fins and at the bottom of said series of fins for registering with the upper and lower headers of the adjacent intermediate sections.

8. A convactor of the inclined sloping fin type comprising a plurality of inclined sections, each having a barrel portion with a header at the top thereof and a header at the bottom thereof and each having sloping fins on the opposite side faces thereof, the fins of one section registering with those of another, end sections at each end of the convactor, each end section comprising a hollow rectangular panel having a diagonally disposed series of fins on the inner face thereof coextensive with and registering with the fins of the adjacent intermediate sections, each end section also having a nipple port on the inner face thereof at the top of said series of fins and at the bottom of said series of fins for registering with the upper and lower headers of the adjacent intermediate sections, 60 and a plurality of connector portions on said end sections in the plane of the vertical center line of the convactor.

9. A convactor of the inclined sloping fin type comprising a plurality of inclined sections, each having a barrel portion with a header at the top thereof and a header at the bottom thereof and each having sloping fins on the opposite side faces thereof, the fins of one section registering 70 with those of another, end sections at each end

of the convactor, each end section comprising a hollow rectangular panel having a diagonally disposed series of fins on the inner face thereof coextensive with and registering with the fins of the adjacent intermediate sections, each end section also having a nipple port on the inner face thereof at the top of said series of fins and at the bottom of said series of fins for registering with the upper and lower headers of the adjacent intermediate sections, and a plurality of connector portions on said end sections in the plane of the vertical center line of the convactor, at least one of said connector portions being on the outside face of the end section and at least one of said connector portions being directed downwardly from the bottom of the end section.

10. A convactor of the inclined sloping fin type comprising a plurality of inclined sections, each having a barrel portion with a header at the top thereof and a header at the bottom thereof and each having sloping fins on the opposite side faces thereof, the fins of one section registering with those of another, end sections at each end of the convactor, each end section comprising a hollow rectangular panel having a diagonally disposed series of fins on the inner face thereof coextensive with and registering with the fins of the adjacent intermediate sections, each end section also having a nipple port on the inner face thereof at the top of said series of fins and at the bottom of said series of fins for registering with the upper and lower headers of the adjacent intermediate sections, and a plurality of connector portions on said end sections in the plane of the vertical center line of the convactor, at least one of said connector portions being on the outside face of the end section and at least one of said connector portions being directed downwardly from the bottom of the end section, the overall width of the end sections being substantially equal to the overall width of the intermediate sections.

11. A convactor of the inclined sloping fin type comprising a plurality of inclined sections, each having a barrel portion with a header at the top thereof and a header at the bottom thereof and each having sloping fins on the opposite side faces thereof, the fins of one section registering with those of another, end sections at each end of the convactor, each end section comprising a hollow rectangular panel having a diagonally disposed series of fins on the inner face thereof coextensive with and registering with the fins of the adjacent intermediate sections, each end section also having a nipple port on the inner face thereof at the top of said series of fins and at the bottom of said series of fins for registering with the upper and lower headers of the adjacent intermediate sections, and a plurality of connector portions on said end sections in the plane of the vertical center line of the convactor, the overall width of each end section being substantially equal to the overall width of an intermediate section.

12. A convactor comprising substantially rectangular hollow end sections having a plurality of tiers of inclined sloping fin convectors disposed therebetween in spaced relation, the end panels having ports which communicate with the inclined sloping fin convectors, the end sections being as high and as wide as the several tiers of convectors.

13. A convactor comprising end sections having a plurality of tiers of inclined sloping fin convectors therebetween, the tiers being in spaced rela- 150

tion to one another, the end sections being as high and as wide as the several tiers of convectors.

14. A convector comprising substantially rectangular end sections in the form of hollow panels with connector portions for connecting the panels into a heating system, a plurality of tiers of inclined sloping fin convectors between the end sections, the end sections having nipple ports for connection with the several tiers of convectors, the 10 inner faces of the end sections also having fins which register with and complement the fins of the adjacent inclined sloping fin convectors.

15. An end section for use with diagonally sloped convector units, comprising a substantially rectangular hollow panel having diagonally arranged bosses on the inner face thereof for establishing communication with the convector units, and having another boss on the interior face offset 20 from the vertical center of the unit to which a fluid conduit may be connected, the inner face of

the section being provided with fins arranged to register with fins on the convector units.

16. A convector comprising substantially rectangular end sections having water circulating passageways therein, and a series of sloping fin convector sections between the end sections, the end sections having nipple ports for connection with the adjacent convector sections, the end sections having fins substantially coextensive with and registering with the fins of the sloping fin convector sections, the end sections having a boss on the inner face thereof offset with respect to the center line of the end sections to which a fluid supply pipe may be connected, said boss permitting the pipes for the convector to be connected thereto between the ends of the convector unit whereby any enclosure for the convector need be only the width of the convector.
